UNITED STATES PATENT OFFICE.

ROBERT WEBB MORGAN, OF NEW YORK, N. Y.

CHECK-BOOK.

SPECIFICATION forming part of Letters Patent No. 521,727, dated June 19, 1894.

Application filed January 31, 1894. Serial No. 498,565. (No model.)

To all whom it may concern:

Be it known that I, ROBERT WEBB MORGAN, a citizen of the United States, and a resident of New York, in the county of New York and State of New York, have invented certain new and useful Improvements in Check-Books, of which the following is a specification.

The invention relates to improvements in check books and particularly to improvements in pocket check books and consists essentially in a book each leaf of which is ruled on its obverse and reverse faces to constitute stubs and deposit columns respectively and provided with a pad of checks, the latter corresponding in number with the number of stubs exposed on the leaf adjoining and the pad being secured in a hinged manner at its outer edge to its leaf so as to normally cover the deposit column whether the book is open or closed and to be capable of being turned outward from over said deposit column when desired.

The object of the invention is to produce a check book of a size adapted to be carried in the pocket, and which possesses all of the facilities for complete and accurate entries in a thoroughly convenient form.

A further object of the invention is to produce a pocket check book of desirable form and which is capable of being manufactured and sold at a reasonable price, the form, arrangement and construction of the parts of the book being such as to render the article convenient in use and easy of manufacture without waste of material.

The invention will be more readily understood from the detailed description hereinafter presented, reference being had to the accompanying drawings, forming part hereof, and in which—

Figure 1 is a face view of an open pocket check book embodying the invention and shown with the pad of checks in their open position exposing the deposit columns or spaces. Fig. 2 is a perspective view of said book disclosing the pad of checks folded inward over the spaces for the deposits and balances and showing one corner of the individual checks turned upward for clearness of illustration; and Fig. 3 is an edge view of one of the leaves of same.

In the drawings, A, B, designate the covers of the book, said covers being oblong in outline and having bound between them the series of leaves C, each of which has at its outer vertical edge the folded section or lip D upon which is secured the pad E of individual checks. Upon the obverse face of each leaf C is the series of printed stubs F, and upon the reverse face of each leaf are the printed deposit spaces or columns G. The folded section or lip D is preferably substantially the same in size and form as the checks E which it carries, and is also substantially co-extensive with the main body of the leaf upon which it is folded, being simply slightly less in width than the leaf. The pad E of checks is secured upon the outer face of the folded section D, so that when the latter is folded upon the main body of the leaf, or leaf proper, the deposit columns will be covered and the checks will face upward opposite to the stubs F on the obverse face of the adjoining leaf C, as shown in Fig. 1. The adhesive substance used to pad the individual checks will be applied along the edge a and also preferably along the edge b of the checks, and hence it will appear obvious that the pad of checks, with the section D, may be turned over and outward in a hinged manner to freely expose the reverse face of the leaf or deposit columns without danger of the checks being accidentally detached by rapid or careless handling.

Each of the pads E will contain as many checks as there are stubs on the adjoining leaf C, and in the present instance, as shown, each pad consists of four individual checks and the obverse face of the adjoining leaf bears four stubs F. When the book is opened at any point both a pad of checks and a series of stubs will appear face uppermost in position for immediate use, the checks extending the full vertical length of the leaves C and the stubs the horizontal width of said leaves, and both being of large convenient size with every facility for ready use. The leaves C with their pads E will be fully used one after another in succession, the deposits and balances being carried on the deposit columns G.

I do not limit the invention to the use of any special number of checks in each pad E nor to the number of stubs F on each leaf C;

nor in every instance to the hinging of the pad of checks at the outer vertical edge of the leaf.

What I claim as my invention, and desire to secure by Letters Patent, is—

1. The check book composed of the leaves each of which is provided on its outer edge with the hinged pad of separate independent checks facing upward when the book is open and retained together by adhesive material applied at the edge of the pad, and each of which leaves bears on its obverse face stubs and on its reverse face the deposit spaces; substantially as and for the purposes set forth.
2. The check book composed of the leaves

each of which is provided at its outer vertical edge with the inwardly folded section and bears on its one face the stubs and its opposite face the deposit columns, combined with the separate independent checks padded together by adhesive material and secured on said folded section; substantially as and for the purposes set forth. 20

Signed at New York, in the county of New York and State of New York, this 30th day 25 of January, A. D. 1894.
